NOSE PAD

Wayne S. Searles, Providence, R. I., assignor to
Universal Optical Corporation, a corporation of
Rhode Island

Application June 18, 1932, Serial No. 617,969

10 Claims. (Cl. 88—48)

This invention relates to a nose pad for an ophthalmic mounting and has for one of its objects to provide a non-metallic covering over a metallic body which covering will be securely held in desired position.

Another object of the invention is the provision of parts so shaped that they will be locked together by reason of the method by which they are assembled.

10 The invention also consists in the method of bending one of the parts to permit the insertion of another part in a recess formed therein and then the return bending of the part so deflected or distorted to a desired finished position which will maintain the parts in locked relation.

15 The invention further consists in the method of locking the parts together by undercutting one part and providing a projection on another part to extend therein, which parts are assembled by 20 the distorting of one of the parts to permit the entrance of the other part therein.

25 With these and other objects in view, the invention consists of certain novel features of construction as will be more fully described and particularly pointed out in the appended claims.

In the accompanying drawing:—

Fig. 1 is a front elevation of a fragmental portion of eye glasses with rims and showing nose guards as mounted in the relative position which 30 they assume with reference to the lens and bridge connecting them.

Fig. 2 is a perspective view of one of the finished nose guards with an arm projecting therefrom.

35 Fig. 3 is a perspective view of the metallic portions of the guard of the structure shown in Fig. 2.

Fig. 4 is a section on line 4—4 of Fig. 2.

Fig. 5 is a plan view looking at the inner surface of the non-metallic portion of the guard alone.

Fig. 6 is a central sectional view of the guard with a recess formed in an inner surface thereof.

Fig. 7 is a view similar to Fig. 6 showing the 45 recess undercut.

Fig. 8 is a sectional view showing the cover as flexed or bent for the insertion of the metallic portion shown in Fig. 3.

Fig. 9 is a sectional view of the metallic portion inserted and the covering bent back.

Fig. 10 is a perspective view of the guard mounted on one of the arms which secure it to the bridge or lens holder.

It is found desirable in the use of nose guards 55 to provide a non-metallic covering for engage-

ment with the nose and in order that such covering may be securely held in place and formed in a single piece of material, I have provided a metallic body for the guard with a flange projecting laterally therefrom and have recessed a solid 60 non-metallic covering with an undercut portion to receive this flange, whereby by bending the covering to spread the edges of the recess I am enabled to insert the metallic body into the recess with its flange in the undercut portion and then 65 by bending the covering back into the desired finished plane, move the overhanging stock on the edge wall of the recess over the flange to secure it in position; and the following is a detailed description of the present embodiment of this invention illustrating the preferred means and method by which these advantageous results may be accomplished.

With reference to the drawing, 10 designates 70 one lens and 11 the other, each provided with a lens holder 12 which may take the form of a rim as here shown. A bridge 13 suitably connects the lens holders, and nose pads 14 are secured to the bridge or lens holder in any desired manner.

75 The nose guards or pads each consists of a body 15 of generally oval or elliptical shape which is provided with a flange 16 flush with the front face 17 thereof, while from the inner face 18 there extends an arm 19 which may be suitably secured to a support for the pad. The cover 20 is preferably 80 formed from some non-metallic material such as celluloid or the like and is recessed at 21 in the first step in the operation as shown in Fig. 6, after which by a further step an undercut 22 is provided in the wall 23 of the recess as illustrated in 85 Fig. 7.

In order that the cover 20 may be secured to the body member 15 I heat and bend or deflect the cover as shown in Fig. 8 to spread the walls 23 of the recess in which deflected position the body member 15 may be set into the recess with its 90 flange 16 in a position to extend into the undercut portion 22 of the recess, after which, by again bending the cover 20 back to substantially a single plane as illustrated in Fig. 9, the stock 24 forming the margin of the recess or opening 21 extends over the inner surface 25 of the flange and 95 securely locks the metallic body 15 in position.

In bending the cover back to form a single plane, heat is applied which so softens the marginal edge 24 as to cause a portion 26 thereof to extend over the body itself and further lock the metallic body in the cover as illustrated in Fig. 4.

100 Any suitable pad support may be provided, such as an arm 27 having an enlarged flat portion 28 105

110

with an opening to receive the arm 19 which may extend therethrough and be headed over as illustrated in Fig. 10 to rockingly support the pad in permanently adjusted position.

6 The foregoing description is directed towards the method and construction illustrated, but I desire it to be understood that I reserve the privilege of resorting to all the equivalent changes to which the construction and method are susceptible, the invention being defined and limited only by the terms of the appended claims.

I claim:—

15 1. A nose pad for an ophthalmic mounting, comprising a body having an outer face and an inner face, an arm secured to and extending from the inner face of said body, a flange of a thickness less than said body extending laterally from said body and about the periphery thereof and a covering over the outer face of the body and extending over the inner surface of said flange to lock the covering on said body.

25 2. A nose pad for an ophthalmic mounting, comprising a body having an outer face and an inner face, an arm secured to and extending from the inner face of said body, a flange of a thickness less than said body extending laterally from said body about the periphery thereof and flush with the outer face, and a covering over said outer face of the body and flange and extending over the inner surface of said flange to lock the covering on said body.

35 3. A nose pad for an ophthalmic mounting, comprising a body having an outer face and an inner face, an arm secured to and extending from the inner face of said body, and a covering over said outer face of the body and extending over the inner surface of said body in a lesser area and in a thickness greater throughout its extent than the thickness of the covering on the outer face of said body, whereby to provide sufficient strength of covering over the inner face to prevent removal of the body from the covering.

40 4. A nose pad for an ophthalmic mounting, comprising a body having an outer face and an inner face, an arm secured to and extending from the inner face of said body, a flange of a thickness less than the thickness of the body extending laterally from said body about the periphery thereof and flush with the outer face and forming a shoulder at the inner surface, and a covering over said outer face of the body and flange and extending over the inner surface of said flange to said shoulder to lock the covering on said body.

45 5. A nose pad for an ophthalmic mounting, comprising a metallic body having an outer face and an inner face, an arm secured to and extending from the inner face of said body, a flange of a thickness less than the thickness of the body extending laterally from said body about the entire periphery thereof and forming a shoulder at the inner surface, and a non-metallic covering over said outer face of the body and ex-

tending over the inner surface of said flange to said shoulder to lock, the covering on said body.

60 6. A nose pad for an ophthalmic mounting, comprising a body having an outer face and an inner face, an arm extending from the inner face of said body, a flange of a thickness less than the thickness of the body extending laterally from said body about the entire periphery thereof and forming a shoulder at the inner surface, and a celluloid covering over said outer face of the body and extending over the inner surface of said flange and engaging said shoulder to lock the covering on said body.

65 7. The method of forming a nose pad which consists in providing a flanged body member, providing an undercut recess in a bendable covering member, bending said covering to convexly arc the bottom of said recess and spread the edges of said recess, inserting the body member therein with its flanges extending beneath its undercut edges and then bending back said covering into substantially a single plane.

70 8. The method of forming a nose pad which consists in providing a body member with a flange extending from its front face, providing a recess of substantially the size and shape of said body in a bendable covering member, undercutting the edge of the recess to provide it substantially the size of said flange, bending said covering to convexly arc the bottom of said recess and spread the edges of said recess, inserting the body member therein with its flanges extending beneath its undercut edges and then bending back said covering into substantially a single plane.

75 9. A nose pad for an ophthalmic mounting, comprising a body having an outer face and an inner face, an arm secured to and extending from the inner face of said body, an integral one-piece pad having an area materially greater than the area of the outer surface of said body with a recess in its inner surface receiving the body, and portions of the pad extending over portions of the inner surface of the body in a lesser area and a greater thickness throughout its extent than the thickness of the portion over the front surface of the body, said thickness providing sufficient strength of covering to lock the same assembled therewith.

80 10. A nose pad for an ophthalmic mounting, comprising a body having an outer face and an inner face, an arm secured to and extending from the inner face of said body, an integral one-piece pad having an area more than twice that of the area of the outer surface of said body with a recess in its inner surface receiving the body, and portions of the pad extending over portions of the inner surface of the body in a lesser area and a greater thickness throughout its extent than the thickness of the portion over the front surface of the body, said thickness providing sufficient strength of covering to lock the same assembled therewith.
